CLAIM

The ornamental design for interconnected centrifugally cast, ductile iron utility pole members, as shown and described.

DESCRIPTION

FIG. 1 is a front elevation view of the present invention.

FIG. 2 is an enlarged elevation view of the central area of FIG. 1.

FIG. 3 is a front elevation view of a second embodiment of the present invention; and,

FIG. 4 is an enlarged elevation view of the central area of FIG. 2.
